ELECTRICAL FITTING

Llewellyn Hopkins, Butler, Pa., assignor of one-half to John V. Cowden, Butler, Pa.

Application March 13, 1940, Serial No. 323,748

8 Claims. (Cl. 260—50)

My invention relates to electrical fittings, and more particularly to those of the plug-in type, wherein a plug having contact fingers is inserted into a receptacle or base having slots for receiving the fingers, and fixed terminals are located at the inner ends of said slots, for electrical contact with said fingers.

In devices of this character, it frequently happens that there will be such loose engagement between the conductor fingers and the terminal elements in the base that slight vibration or movement will cause interruption of the electrical circuit. Again, a slight pull on the wires or cable to which the plug is connected may cause the plug to be withdrawn from the base, or the receptacle may be mounted in a ceiling and the plug may fall out.

My device is of general utility and in addition to being desirable for household and other general uses, it embodies a safety feature which will reduce hazards to employees in mills, one specific use being in the case of cranes and magnetic lifting devices, where accidental interruption of electrical current may result in loads which are being lifted and transported dropping upon workmen or machinery.

My invention has for its object the provision of an improved means whereby the electrical plug will be locked automatically and firmly in the base or receptacle when the switch is closed.

In the accompanying drawing, Figure 1 is a side view showing the plug in section and also showing the base; Fig. 2 is a view showing certain of the parts of Fig. 1 removed from the casing; Fig. 3 is a perspective view showing certain of the locking elements of Figs. 1 and 2, independently of the switch elements; Fig. 4 is a plan view of the base of Fig. 1, and Fig. 5 is a detail view of a portion of the structure of Fig. 3.

The apparatus comprises a base or receptacle 5 which may be of conventional form in that it can be screwed into a socket that has terminal or contact members with which the conductor elements 6 and 7 of the base will make electrical contact. The base is also provided with slots or holes 8 and 9 for the reception of contact fingers carried by the plug, so that the fingers will engage the usual conductors in the base, for completing the circuit through the fingers and the elements 6 and 7. The parts thus far specifically referred to are of any well-known conventional form. It will be understood that bases of other forms than that just described may be employed, if they have recesses or openings 8 and 9 for the reception of contact fingers.

The plug may be of somewhat conventional form in general appearance, in that it comprises an outer metallic case 10 lined with insulating material 11 and provided with contact fingers or prongs 12 and 13 that can be inserted into the openings 8 and 9, and also being provided with a switch for completing a circuit from conductors 14 and 15 through the contact members 12 and 13. The switch is here shown as of the single pole, 10 two-point break type and comprises a blade 16 that is pivotally mounted at 17 upon one leg of a bracket 18 of inverted U-form, the switch blade being insulated at 17 from the bracket. Upper switch jaws are secured at 20 to the bracket 18, 15 but are insulated therefrom and have electrical connection with the wire 14 by a terminal screw at 20. The lower switch jaws 21 are secured to the lower portion of the bracket 18 by a terminal screw 22, the jaws and the screw being insulated from the bracket. The prong 12 has electrical connection through the screw 22 with the jaws 21.

A switch lever 23 is pivotally connected at 24 with the opposite leg of the bracket 18 and pivotally carries a link 25 that has rigid connection at 26 with an arm 27 that is pivotally connected with the switch blade 16, the arm being insulated from the link 25. The wire 15 is connected to the upper end of the finger 13, the said finger being secured to the bracket 18 by an insulated connection at 29. It will be seen that as the switch lever 23 is moved up and down, the blade 16 will be oscillated to make and break the circuit through the wire 14 and the finger 12.

35 A screw-threaded ferrule 31 has threaded connection with a bushing 32 which is secured in the upper end of the switch casing and extends through a hole formed in the upper end of the bracket 18 and has threaded connection at 33 with a gripping device 34, which is shown in detail in Fig. 3. The gripping device has two pairs of jaws 35 and 36 that are of spring-like material, the jaws being yieldably urged toward expanded position by interposed coil springs 37 and 38 respectively.

The link 25 carries at its lower end a pair of yokes 39 and 40 that embrace the jaws 35 and 36 respectively, so that when the switch lever is moved downwardly to rock the switch blade 16 in a counter-clockwise direction to bridge the switch jaws 19 and 21, the yokes 39 and 40 will also be moved down to draw the jaws of each pair toward one another.

50 As indicated more clearly in Fig. 5, the yokes 39 and 40 have antifriction rollers 43 journaled

therein, to reduce friction with the members 35 and 36, and the members 35 and 36 have recesses 44 formed therein, so that the yokes will be yieldably held in their lower positions, and the switch blade 16 consequently yieldably held closed. Also, the expansive force of the springs 37 and 38, when the yokes are in their upper position, will tend to hold the movable switch parts with the blade in open position—against accidental closing.

When the plug has been placed in assembled relation with the base 5, and with the fingers 12 and 13 in electrical contact with the conductor elements in the base 5, movement of the switch lever 23 in a clockwise direction about its pivot 24 will move the switch blade 16 into its closed-circuit position and will also move the yokes 39 and 40 downwardly to draw the jaws together, so that the jaws will engage beneath the heads of anchoring studs 42 that are embedded in or otherwise rigidly connected with the base 5, so that the plug will be held firmly in assembled relation with the base 5, thus insuring against accidental displacement therefrom or relative vibration. This anchored connection will be maintained so long as the switch remains closed.

I claim as my invention:

1. In an electrical fitting, the combination with a base and a plug having conductor fingers insertible into the base, of a pair of headed retaining elements projecting outwardly from the base, hook members carried by the plug and each having one end connected to a fixed portion of the plug, and a slideable yoke-like member for effecting movement of the other ends of said hook members into hooked engagement with said retaining members.

2. In an electrical fitting, the combination with a base and a plug having conductor fingers insertible into the base, of a switch carried by the plug, a retaining element on the base, a hook member having one end connected to a fixed portion of the plug, and means operated through circuit-closing movement of the switch, for moving the other end of the hook member into hooked engagement with said retaining element and rigidly maintaining said member in such position.

3. In an electrical fitting, the combination with a base having conductor elements and a plug having conductor elements positioned to engage the first-named elements when the plug and the base are in assembled relation, of retaining shoulders on the base, hook members carried by the plug and each having one end connected to a fixed portion of the plug, and means for moving the other ends of the hook members into position behind the shoulders to effect interlocking engagement therewith and rigidly maintaining said members in such position.

4. In an electrical fitting, the combination with a base having conductor elements and a plug having conductor elements positioned to engage the first-named elements when the plug and the base are in assembled relation, of retaining shoulders on the base, hook members carried by the plug and each having one end connected to a fixed portion of the plug, and a yoke movable to effect lateral movement of the other ends of the

hook members to and from interlocking position behind the said shoulders.

5. In an electrical fitting, the combination with a base having conductor elements and a plug having conductor elements positioned to engage the first-named elements when the plug and the base are in assembled relation, of retaining shoulders on the base, hook members carried by a fixed portion of the plug, a yoke movable to effect lateral movement of the hook members to and from interlocking position behind the said shoulders, and a lever pivotally mounted on the base, for operating the yoke to move the hook members into position behind the shoulders to effect interlocking engagement therewith.

10 6. In an electrical fitting, the combination with a base having conductor elements and a plug having conductor elements positioned to engage the first-named elements when the plug and the base are in assembled relation, of retaining shoulders on the base, hook members carried by a fixed portion of the plug, a yoke movable to effect lateral movement of the hook members to and from interlocking position behind the said shoulders, a lever pivotally mounted on the base, for operating the yoke to move the hook members into position behind the shoulders to effect interlocking engagement therewith, a switch actuated by said lever to open the switch when the lever is moved to release the hooks, and means for yieldably holding the lever in its open-switch position.

20 7. In an electrical fitting, the combination with a base having conductor elements and a plug having conductor elements positioned to engage the first-named elements when the plug and the base are in assembled relation, of retaining shoulders on the base, hook members carried by a fixed portion of the plug, a yoke movable to effect lateral movement of the hook members to and from interlocking position behind the said shoulders, a lever pivotally mounted on the base, for operating the yoke to move the hook members into position behind the shoulders to effect interlocking engagement therewith, and a switch operated through movement of said lever, in a direction to close the circuit, when the hook members are moved into said interlocking position.

25 8. In an electrical fitting, the combination with a base having conductor elements and a plug having conductor elements positioned to engage the first-named elements when the plug and the base are in assembled relation, of retaining shoulders on the base, hook members carried by a fixed portion of the plug, a yoke movable to effect lateral movement of the hook members to and from interlocking position behind the said shoulders, a lever pivotally mounted on the base, for operating the yoke to move the hook members into position behind the shoulders to effect interlocking engagement therewith, a switch operated through movement of said lever, in a direction to close the circuit, when the hook members are moved into said interlocking position, and means for yieldably holding the switch in open position when the yoke is in position to effect release of the hook members from said shoulders.

LLEWELLYN HOPKINS.
